UNITED STATES PATENT OFFICE.

BENJAMIN J. HASTINGS, OF TAUNTON, MASSACHUSETTS, ASSIGNOR TO HASTINGS SIGNAL & EQUIPMENT COMPANY, OF BOSTON, MASSACHUSETTS, A CORPORATION OF MASSACHUSETTS.

HOLDER FOR RAILROAD-BRIDGE WARNINGS.

Application filed September 6, 1924. Serial No. 736,303.

To all whom it may concern:

Be it known that I, BENJAMIN J. HASTINGS, a citizen of the United States, residing at Taunton, county of Bristol, State of Massachusetts, have invented a certain new and useful Improvement in Holders for Railroad-Bridge Warnings, of which the following is a specification, reference being had therein to the accompanying drawings.

10 The invention relates to an improvement in holders for railroad bridge warning. Bridge warnings, so called, are suspended over the track a short distance from an overhead bridge to serve as a warning to 15 brakemen on top of freight cars of the near approach to the bridge. These warnings usually consist of wire hangers pivotally connected with an arm extending crosswise of the track in such manner that they may 20 swing in the direction lengthwise of the track. These wires are usually a foot or so in length and there is secured to the lower end of each wire a rope which hangs down low enough so that if a brakeman is standing or sitting on the top of the car the rope 25 will hit him in time to enable him to flatten himself on the car and avoid striking the bridge.

The present invention is an improvement 30 upon the invention shown and described in Patent No. 1,207,550, granted to me December 5, 1916. The object of the invention of said patent was to provide a simple device to be attached permanently to the arm overhanging the track and of such construction that the wires may be readily attached to or detached from said holder by an operative standing on the ground and using a pole. One drawback to the holder shown in said 35 prior patent is that the latch is dependent solely on gravity to hold the latch in position to retain the bridge warning. As a result of such construction it sometimes happens that due to vibration or other causes 40 the latch is tripped and the holder with the bridge warning is accidentally released. The object of the present invention is to provide means for preventing such accidental detachment and at the same time permit 45 the ready removal or replacing of the bridge warning when desired.

The invention will be fully understood from the following description when taken in connection with the accompanying draw-

ings, and the novel features thereof will be 55 pointed out and clearly defined in the claims at the close of this specification.

In the drawings:

Fig. 1 is an elevation of an arm and post and a series of bridge warnings attached to 60 said arm by means of devices embodying the invention.

Fig. 2 is an elevation on a larger scale than Fig. 1 of one of the holders embodying the invention, detached from the supporting arm.

Fig. 3 is a section on line 3—3, Fig. 5, showing one of the wire hangers supported by the holder.

Fig. 4 is a view showing the latch of the 70 holder partly tipped up on its pivot while the hanger wire is being introduced or released.

Fig. 5 is a section on line 5—5, Fig. 3.

Fig. 6 is a bottom plan view of one of the 75 holders.

Fig. 7 is a detail view of the spring which maintains the latch in normal position when the device is in use.

Referring to the drawings, 1 represents 80 a post having attached to the upper end thereof an arm 2 which projects crosswise above the track and which is usually connected at its other end with a post similar to the post 1. On the under side of the arm 85. 2 is a wooden stringer 3 to which are secured the special devices or holders which embody the invention. The holder has a head 4 provided with suitable means for attaching it to the stringer 3. The means 90 shown consists of a screw 5.

The head 4 is formed with a vertical slot 6 extending up from the under side, said vertical slot being of only slightly greater horizontal width than the thickness of the 95 wire 7 to which the rope 8 is secured and of sufficient length so that the loop or eye 9 formed at the upper end of the wire may be easily entered into the slot 6, as shown in Fig. 5. The said slot preferably extends up 100 into the head a distance about equal to the diameter of the eye 9 of the wire. One side wall of the slot 6 is formed with a slot 10 extending therethrough at right angles to the slot 6 and between ears 11, 11 between 105 which is pivoted a latch member 12 on a pivot pin 13. Said latch has an arm 14 on one side of the pivot 13 which, in its

normal position, extends entirely across the slot 6 and has an arm on the opposite side of the pivot with a finger 15 which projects out through the slot 10 so that the latch 5 may be tripped by an operator by means of a pole having a hook. The said latch 12 may be turned on its pivot so as to swing the arm 14 upward and inward into the slot 10 and out of the slot 6. A stop is provided to 10 limit the downward swing of the arm 14 so that in its lowermost position it will extend crosswise of the slot 6 to support the hanger wire. The stop mechanism for thus limiting the downward movement of the 15 latch is formed by the shoulder 16 at the lower end of the wall 17 which connects the two ears 11, 11 at their upper portions, the said ears extending some distance below the wall 17 so that the arm 14 can project 20 through the slot 10. In order to hold the latch arm 14 crosswise of the slot 6 there is provided a spring which shall have sufficient tension to normally retain the latch in the proper position and yet be sufficiently flexible to yield to the upward pressure of a suitable device to trip the latch when it is desired to detach the hanger or to insert a new one. Any suitable form of spring may 25 be used for this purpose. The preferred form is that shown in the drawings. Said spring is preferably made of wire doubled back in the middle, as shown at 18 to form a loop at the bend, the two ends of the wire being secured together as shown at 19. The 30 doubled member thus formed is bent into substantial U-shape as shown in Fig. 6 forming two pairs of leg members 20, 21, the upper ends of one pair of leg members being joined together by the bend 18 in the middle 35 of the wire and the upper end of the other pair of leg members being united at 19. The spring is inserted in the slot 10 between the ears 11 of the holder in such manner that the two pairs of leg members of the spring 40 straddle the latch, one pair of leg members 20, 21 being in one side and the other pair being on the other side. The end 19 rests against the inner face of the wall 17, and the upper edge of the arm 14 will engage in 45 the loop 18 and the loops 22 at the base of the two leg members of the spring will engage the under side of the pivot 13, as clearly shown in Figs. 2, 3, 4 and 5. The upper end 19 of one leg member is always 50 kept stationary by its engagement with the wall 17 of the holder while the other leg may be flexed by turning the latch member on its pivot. By pulling down on the hook finger 55 15 of the latch member the arm 14 will be

turned up, thereby turning up the leg member 60 21 of the spring while the leg 20 is stationary, thus putting the spring under greater tension. When the latch arm 14 is turned up by pulling down on the finger 15 the eye 9 of the hanger may be inserted or 65 withdrawn as the case may be, and when the downward pull on the latch is released the tension of the spring will cause the movable arm 21 of the spring to spring back and thereby carry with it the arm 14 of the latch 70 crosswise of the slot 6.

While I have specifically described one form of spring for this purpose, it is obvious that other forms of spring may be used to accomplish the desired purpose and it is 75 to be understood that the form of spring shown and described is merely illustrative and the invention is not limited to any particular form of spring.

What I claim is:

1. A holder for a bridge warning hanger having a body formed with a slot to receive the eye of a hanger, a latch lever pivoted to said body and having one arm which normally extends crosswise of said slot, said 85 latch being movable on its pivot to swing said arm up out of the slot to admit the eye of the hanger therein and a spring which is put under tension by turning the latch arm upward and which pulls the said latch 90 arm back through the eye when the upward pressure is released and holds said latch lever transversely of the slot to support the hanger.

2. A holder for a bridge warning hanger 95 having a body formed with a slot to receive the eye of a hanger, a latch lever pivoted to said body and having one arm which normally extends crosswise of said slot, said latch lever being movable on its pivot to 100 swing said arm up out of the slot to admit the eye of the hanger therein and a spring which is put under tension by turning the latch arm upward, and which pulls the said latch arm back through the eye when the 105 upward pressure on the latch arm is released and holds said latch lever transversely of the slot to support the hanger, said spring being of U-shape having one leg which engages with a wall of the holder, the upper 110 end of the other leg of the spring engaging with the latch arm of the lever to hold it down, and a pivot for the latch lever which is engaged by the loop formed by the base of the U-shaped spring.

In testimony whereof I affix my signature.

BENJAMIN J. HASTINGS.
